UNITED STATES PATENT OFFICE.

ARTHUR D. SABORSKY, OF LAKWOOD, OHIO, ASSIGNOR TO CHISHOLM-MOORE HOIST CORPORATION, OF BUFFALO, NEW YORK, A CORPORATION OF NEW YORK.

TROLLEY TRACK SWITCH.

Application filed November 14, 1927. Serial No. 233,011.

This invention relates to a track switch for over head trolleys, such as used in industrial plants. It is quite customary to provide a track-way comprising the lower flange of an I-beam suitably suspended. When branches run off from such a track-way a swinging section of the I-beam is provided to connect the common line with either branch. As ordinarily constructed such swinging section is hinged at the end of the common beam with more or less of a gap between their flanges, resulting in a jolt as the trolley travels across this gap. This jolt is frequently troublesome, as when conveying delicate machinery or a liquid load. Moreover, the lateral guide wheels of a trolley are frequently caught on the projecting ends of a track-way adjacent the hinge, resulting in difficulty in movement and sometimes injury to the trolley.

It is the object of this invention to provide a switch which, without expensive machining, will avoid the objections noted and will furnish a continuous smooth track-way from the main line to either of a plurality of branches, and will also provide a continuous guide for the guide wheels. I thus obviate either a vertical or a lateral jolt. The means by which I accomplish this result constitute the present invention. They will be hereinafter more fully described in connection with the drawings which illustrate a preferred embodiment.

In the drawings Fig. 1 is a plan of an I-beam track way equipped with my precision switch; Fig. 2 is a side elevation of such a track way and switch; Figs. 3 and 4 are horizontal sections, on a larger scale in the plane indicated by the line 3-3 on Fig. 2 and showing the switch point in different positions; Fig. 5 is a fragmentary horizontal section adjacent the hinge, just above the upper flange of the I-beam, as indicated by the line 5-5 on Fig. 6; Fig. 6 is a vertical cross section in the plane indicated on the line 6-6 in Fig. 3; Fig. 7 is a fragmentary longitudinal vertical section in the plane indicated by the line 7-7 in Fig. 4.

As shown in the drawings, 10 designates the main track I-beam and 11 and 12 two branch track I-beams; 13 designates the switch point I-beam which may connect the track 10 with either track 11 or 12, this switch point being hinged to the end of a track 10 and adapted to register with either I-beam 11 or 12. While my invention is concerned with features of

the lower flanges adjacent the hinge, it will be clearer to first describe the whole support of the switch point.

As shown the switch point is hinged to the beam 10 by a pin 20 secured to the beam 10 by a strap 21 and engaging an opening in an overlapping strap 22 secured to the switch point 13. As shown the pin 20 has a head 24 and is thus clamped tight against the top of the I-beam 10 by the strap 21, which is bolted to the top of the I-beam by bolts 26. The strap 22 is bolted to the upper flange of the switch point 13 by bolts 28.

The free end of the switch point 13 is provided with suitable means for supporting it in registration with either branch beam or while traveling from one to the other. To this end I have shown a projecting plate 30 on the switch point which overhangs and rests on an arcuate seat 32 on a transverse block 33 secured to the two branch beams. As shown the block 33 is bolted to the upper flanges of these beams by the bolts 34 and 35.

A brace rod 40 is shown as connecting the main track 10 with the two branches, this rod being mounted at one end in an ear 29 on the hinge strap 21 and at the other end in an ear 37 on the casting 33, suitable nuts applying proper tension to the rod.

In Fig. 2, I have indicated at 50 a four wheel trolley adapted to travel on the overhead structure, this trolley having a suitable frame and four supporting wheels, of which two are shown at 51. These wheels may have flanges as is usual, but I prefer wheels without flanges, the trolley being guided by means of suitable guide wheels 52 on vertical pivots which engage flanges of the different I-beams, as illustrated, for example, in Patent No. 927,994 to E. Y. Moore.

So much of the construction as has been described is of standard form and only incidentally is concerned with my invention, which relates particularly to means enabling the smooth travel of the trolley from the beam 10 to the switch point 13 and vice versa. Such means will now be described.

The lower flange 60, the I-beam 10 adjacent its end is cut away for a portion of the width of the flange, as illustrated at 61 in Figs. 3 and 4. The lower flange 70 of the switch point 13 at the end adjacent the I-beam 10 has its outer portions extending beyond the intermediate portion and thus projecting into the recesses 61. The vertical web of the

I-beam 13 terminates some little distance from the end of the web I-beam 10, and the intermediate portion of the flange 70 is cut away as at 73 adjacent the end of the vertical web.

- It results from the construction described that the projecting tongues 71 on the switch point always have some portion laterally opposite the remaining portions of the flange 60 on opposite sides of the hinge axis. Accordingly, as the trolley travels across the junction its wheels engage the flange of the beam onto which they are about to travel before leaving the flange of the beam on which they have been traveling, an intermediate zone of the wheel tread being over the gap. Thus Fig. 4 indicates at 51 two of the supporting wheels which are resting partly on the central tongue or remaining end portion of the flange 60 of the I-beam 10 and partly on the straddling tongues 71 of the switch beam 13. The result is that a smooth continuous track is provided, allowing the travel of the trolley without jolt irrespective of the switch point, and at the same time plenty of clearness is allowed to enable the ready swinging of the switch point without requiring an accurate machining operation of the flanges.
- To further insure the level passage from one flange to the other, I secure a plate 80 to the underside of the I-beam 60 (as by rivets 81) which plate projects beneath and engages the underface of the flange 70 of the switch point. To prevent burrs at the ends of the central and straddling tongues on the flanges 60 or 70 from interrupting the smooth travel, I bevel off the ends of such tongue at 65, 66 and 75 and 76.
- To prevent lateral shifting of the trolley as it travels across the junction of the switch point with the common I-beam 10, I make the plate 80 beneath the I-beam 10 the full width of the flange 60 and continue it at this width across the gap to a point at each edge where the plate extends beneath the tongue 71 when the latter has swung into its extreme position away from the flange 60. From these points the edges 82 converge sufficiently so that they are never beyond the other member irrespective of the position of the latter. Accordingly, the guide rollers 52 always engage the edges of the plate 80 when they are not in engagement with either the flange 60 or the flange 70. Thus there is no chance for a lateral shift in passing between the common I-beam and the switch point.
- It will be seen that by the simple provision shown, as above described, I provide a smooth track-way enabling the passage of the trolley without jolt, and I accomplish this without requiring machine work of the I-beam flanges. These may be cut off roughly, and the expense of machining concentric convex and

concave arcs in the ends of the track and switch members is avoided. My track way may be installed and supported in the usual manner and without extra expense at the switch. The clearance between the webs of 70 the I-beams 10 and the switch point 13 allows ample space for the passage of the wheels of the trolley across the junction without engaging either web. For the sake of completeness, I have shown a suitable lock 75 at the free end of the switch point. This comprises a bolt 90, slidably mounted in clips 91 on the plate 30, and pressed by a spring 92 so as to engage either of a pair of openings 93 in a flange 94 on the bracket 33. The 80 bolt may be withdrawn by pulling either of a pair of cords 95 which are connected to bell cranks 96 which are connected with the bolt. These cords pass downwardly through suitable wings 97 projecting laterally from 85 the switch point. The cords 95 provide means for withdrawing the bolt, also for drawing the switch point toward the operator, suitable abutments 38 on the bracket 33 limiting the movement. The wings may 90 also carry stop plates 98 closing either track way 11 or 12 when the switch point 13 is registering with the other track way.

I claim:

1. A trolley track-way having a main member and a swinging member adapted to connect the same with either of a plurality of track-ways, characterized by the main member and swinging member having overlapping non-contacting straight-sided tongues 100 on substantially the same level whereby a trolley wheel may rest at the same time on both members.
2. A suspending trolley track-way comprising a main member and a switch member 105 end to end and hinged together, one of said members having a pair of spaced projecting tongues which overlap an intermediate tongue on the other member irrespective of the mutual relation of said members, said intermediate tongue being materially narrower throughout its length than the width of the member carrying it, whereby a wheel may rest simultaneously on the intermediate tongue and on one of said pairs of tongues. 110
3. The combination of a stationary I-beam, a movable I-beam constituting a switch member, the lower flanges of said I-beams constituting a track-way for a trolley, flanges of one of said beams being cut away in straight 120 lines at the corners and the flanges of the other beam projecting in the form of laterally spaced tongues to occupy the recesses provided by such cut away corners.
4. In a trolley track-way, the combination 125 of an I-beam having the intermediate portion of its double lower flange substantially co-terminus with the web but having edge portions adjacent the end cut away to leave a tongue, and a co-operating I-beam having 130

- its lower flange substantially at the same level with the lower flange of the I-beam first mentioned, and having the intermediate portion of its double lower flange cut away for 5 a materially greater width than said tongue, and its web cut away substantially co-terminus therewith, whereby the last mentioned flange continues in the form of tongues adjacent the edges which project freely into the 10 cut away space of the first mentioned flange and lie alongside of said tongue without contacting therewith, there being means for swinging one of said beams with reference to the other on a vertical axis.
- 15 5. A trolley track-way comprising two structural members providing lower flanges on which the trolley wheels may run, and a hinge pin connecting said members and mounted in a pair of overlapping straps connected to them respectively, the end portions of said flanges being cut away non-concentrically of the hinge pin and in a manner to provide constantly overlapping tongues.
6. The combination of a pair of I-beams 25 adapted to register end to end, a pair of straps secured to the upper flanges of the I-beams and overlapping each other, a hinge pin adjacent to the end of one of the I-beams and mounted in the two straps, the lower flange of one of the I-beams adjacent its corners being cut away to form oppositely disposed shoulders having an extended neck portion therebetween, and the intermediate portions of the lower flange as well as the 30 web of the other I-beam being cut away, whereby the latter I-beam has tongues adjacent the edges of its flanges, which tongues always straddle the neck portion of the first mentioned I-beam, but at variable distances 35 therefrom according to the mutual position of the I-beams.
7. The combination, with a trolley track-way comprising two members hinged together, each having a portion which the trolley wheels would engage cut away adjacent the ends to provide overlapping straight-sided non-contacting tongues, and a plate secured to the underside of one of the said members and projecting beyond the end 40 thereof to engage the underside of the other member.
8. A suspending trolley track-way comprising a main member and a switch member end to end and hinged together, one of said 45 members having a pair of projecting tongues on opposite sides of an intermediate recess, the ends of said tongues being longitudinally opposite inwardly directed shoulders on the other member which leave between said 50 tongues an extended neck portion straddled by the tongues on the first named member irrespective of the mutual position of said members, and a plate secured to the underside of one of said members and projecting beneath the other member.
- 55 9. The combination of a pair of I-beams adapted to register end to end, a pair of overlapping straps secured to the upper flanges of the I-beams, a hinge pin mounted in the two straps, the lower flange of one of the I-beams 60 being formed into a tongue, and the lower flange of the other I-beam being cut away intermediately, whereby the latter I-beam has tongues adjacent the edges of its flanges, which tongues always straddle the tongue of the first mentioned I-beam, and a plate secured to the lower flange of one of the I-beams and projecting beyond the end thereof and beneath the underside of the lower flange of the other I-beam.
10. The combination of a pair of track-ways hinged together, said track-ways having the end portions of their wheel supporting surfaces formed to provide overlapping tongues and a plate secured to the underface of one of the members and projecting endwise beneath the underface of the other member to which it is secured to the region occupied by the tongue of the other member when such tongue is in its most distant position from the uncut edge portion of the first member.
11. A track-way comprising a pair of members hinged together and having registering wheel supporting surfaces and a plate secured to the underside of one of the members and extending beneath the other member, said plate having the edges of its projecting portions parallel with each other for a certain distance and then converging beneath the other member, whereby notwithstanding the change in the mutual position of said members said plate preserves the guiding effect of the edges of the track-ways across the gap between the track-ways without projecting laterally beyond such edges.
12. A trolley track-way comprising two I-beams, placed end to end with their webs vertical, means carried by the upper flanges of said I-beams for hinging them together, the lower flange of one of the I-beams being 70 cut away at the corners adjacent the end and the lower flange and web of the other I-beam being cut away intermediately, whereby one member provides a central tongue and the other member a pair of edge tongues, which tongues overlap but are out of contact with each other in all positions of said members, and a plate secured to the underflange of one of the I-beams and projecting beneath and engaging the underface of the lower flange of the other I-beam, said plate being the full width of the beam to which it is secured where it extends across the gap between the cut away corners and the end of the edge tongues and having converging edges in the region adapted to lie beneath the other member.
13. A trolley track-way comprising two beams, placed end to end and hinged together and having wheel-supporting surfaces and a plate secured to one of the beams and pro-

jecting beneath the other beam, said plate being the full width of the beam to which it is secured where it extends across the gap between the wheel-supporting surface of the 5 beams, and having converging edges in the region adapted to lie beneath the other beam combined with a trolley having flangeless supporting wheels adapted to rest on the I-beam flanges and having guide rollers 10 adapted to engage the edges of such flanges and also engage the edges of said plate at the gap between such flanges.

14. A trolley track-way comprising two I-beams, placed end to end with their webs 15 vertical, means carried by the upper flanges of said I-beams for hinging them together, the lower flange of one of the I-beams being cut away at the corners adjacent the end and the lower flange and web of the other I-beam being 20 cut away intermediately, whereby one member provides a central tongue and the

other member a pair of edge tongues, which tongues overlap but are out of contact with each other in all positions of said members, and a plate secured to the underflange 25 of one of the I-beams and projecting beneath and engaging the underface of the lower flange of the other I-beam, said plate being the full width of the beam to which it is secured where it extends across the gap between the cut away corners and the end of edge tongues and having converging edges 30 in the region adapted to lie beneath the other I-beam, combined with a trolley having flangeless supporting wheels adapted to rest 35 on the I-beam flanges and having guide rollers adapted to engage the edges of such flanges and also engage the edges of said plate at the gap between such flanges.

In testimony whereof, I hereunto affix my 40 signature.

ARTHUR D. SABORSKY.
